UNITED STATES PATENT OFFICE.

EMANUEL SCHWAB, OF NEW YORK, N. Y.

DESIGN FOR A GLASS CIGAR AND ASH TRAY.

No. 38,072.

Specification for Design.

Patented June 12, 1906.

Application filed April 23, 1906. Serial No. 313,356. Term of patent 7 years.

To all whom it may concern:

Be it known that I, EMANUEL SCHWAB, a citizen of the United States, residing in the borough of Manhattan, city, county, and State of New York, have invented a new, original, and ornamental Design for Glass Cigar and Ash Trays, of which the following is a specification.

The nature of my design is fully represented in the accompanying drawings, to which reference is made, in which—

Figure 1 is a top view, Fig. 2 a side elevation, and Fig. 3 an end elevation, of a tray embodying my design.

I claim—

The ornamental design for a glass cigar and ash tray as shown.

EMANUEL SCHWAB.
